UNITED STATES PATENT OFFICE

2,587,473

HYDRAULIC DEBARKER

Joseph E. Holveck, Upper Montclair, and Arthur G. Rockwood, Nutley, N. J., assignors to Washington Pump and Machinery Corporation, Harrison, N. J., a corporation of Delaware

Application June 19, 1948, Serial No. 34,114

12 Claims. (Cl. 299—57)

1

This invention relates to the removal of bark from logs and more particularly to the removal of the bark by a high velocity jet of water independently of any mechanical assisting means.

Heretofore, methods and apparatus for removing the bark from logs have been employed both by projecting a high velocity jet of water against a log perpendicularly to the longitudinal axis of the log, moving the jet of water along the log and indexing or rotating the log one step and repeating the operation, thus removing the bark in longitudinal increments. This method of bark removal is relatively slow and expensive in that several passes of the jet of water are required to remove the bark from a log.

Then, also, the method and apparatus of removing the bark from logs by moving a log longitudinally past one or more nozzles projecting high velocity water against the log has been employed. This method has the disadvantage of high consumption of high velocity water, as well as the fact that the operator is unable to determine whether the log has been properly cleaned of all bark and cambium until the entire log has passed the nozzles.

Still another method of removing the bark from logs, heretofore employed, is that of supporting the log upon centers, much like the centers of a lathe, rotating the log on these centers and projecting a jet of high velocity water against the log tangentially of the circumference of the log and at the same time utilizing in conjunction with the jet of water, scoring means to score the bark and scouring rollers to brush and scour the log after it has been subjected to the action of the jet of water. The disadvantages of such methods are the cost of the time-consuming operation of centering the logs, the inadaptability of such apparatus for removing the bark from logs having projecting stub limb, and the inefficient effect of the scouring and brush members when the log is out of round. All of these add up to time-consuming costly operation of the removal of bark from practically perfect round logs and the inefficient imperfect removal of bark from logs which are out of round or have limb stubs on them.

It is an object of the present invention to provide an apparatus for removing the bark from logs, which apparatus is simple in construction in comparison with its predecessor successful bark removers, and an apparatus which will completely remove the bark and cambial layer from a log in a minimum amount of time with a minimum consumption of high velocity water and one

which will effectively and completely remove the bark regardless of limb stubs or the roundness of the log.

More specifically, the present invention comprises a log debarking apparatus which employs the method of moving a high velocity and vertical jet of water in the direction of the longitudinal axis of a horizontally-positioned log, with the jet impinging in its greatest dimension, in a plane parallel to the longitudinal axis of the log and rotating the log by means of contact rollers during the longitudinal movement of the jet of high velocity water to remove the bark in substantially spiral increments and to completely debark the log in one pass of the jet of water without the aid of mechanical assistance such as by means of grouters or scorers and brushes or scouring means.

Another object of the invention is the provision of a log barking apparatus which embodies a novel and comparatively simple structure for supporting the nozzle which projects the jet of high velocity water and of supplying or delivering such water to the nozzle.

Another object of the present invention is the provision of a hydraulic debarking apparatus for logs which provides means for variable barking of effectiveness, to meet variable conditions of bark removal from logs. The resistance to barking or removal of the bark from logs varies with the type and age of the logs, thickness of the bark, the season of the year when the tree was cut, the lapse of time between the cutting of the tree and the removal of the bark from the log as well as other factors.

More specifically, the present invention embodies means for varying the angle of impingement of a chisel-like jet of high pressure water with respect to a plane passing through the longitudinal center of a log and means for varying the distance of the nozzle from the log for varying the jet action by varying the mass and velocity of the jet on a confined area of the log to provide variable barking effectiveness as above referred to.

With these and other objects in view, as may appear from the accompanying specification, the invention consists of various features of construction and combination of parts, which will be first described in connection with the accompanying drawings, showing a hydraulic debarker of a preferred form embodying the invention, and the features forming the invention will be specifically pointed out in the claims.

In the drawings:

Figure 1 is a side elevation of the improved log debarking apparatus.

Figure 2 is a top plan of the log debarking apparatus.

Figure 3 is an end view of the log debarking apparatus.

Figure 4 is a side elevation partly in section of the nozzle structure and its carrier.

Figure 5 is a top plan partly in section of a nozzle structure and its carrier.

Figure 6 is a vertical section taken on the line 6—6 of Figure 4.

Figure 7 is a detailed cross section taken on line 7—7 of Figure 6.

Figure 8 is a detailed section of a control valve structure employed in the log debarking apparatus.

Figure 9 is a vertical section through the nozzle proper employed in the debarking apparatus.

Figure 10 is a vertical section through the nozzle taken at right angles to the view shown in Figure 9.

Figure 11 is a bottom plan of the nozzle.

Figure 12 is a diagrammatic view showing the inner section of the impinging pressure water jet and resultant kerf on top of a log parallel with a plane passing through the longitudinal section of a log.

Figure 13 is a view similar to Figure 12 showing the resultant kerf on top of a log at right angles with a plane passing through the longitudinal section of a log.

Referring more particularly to the drawings, the improved hydraulic log debarking apparatus includes a plurality of log-turning or rotating rollers 1 arranged in parallel sets on suitable shafts 2. The rollers 1 and shafts 2 are rotated from a suitable prime mover such as an electric motor 3 through suitable gearing 4. The logs, one of which is indicated in dotted lines at A in Figures 1 and 3 of the drawings, are rolled laterally upon the rolls by any suitable type of mechanism (not shown) and are discharged laterally therefrom by any suitable type of mechanism (not shown).

A supporting structure 5 is supported above the log rotating rollers 1 and it has a pair of parallelly extending tracks 6 carried thereby over which the flanged wheels 7 of a nozzle carriage 8 travels. The nozzle carriage 8 is moved longitudinally on the rails 6 by means of any suitable propelling structure such as a cable 9 having its ends connected to opposite ends of the carriage 8. The cable 9 passes about suitable guide rollers 10 which are rotated from a suitable prime mover 11, such as an electric motor through a suitable set of gearing 12 or other power transmitting means so as to move the carriage 8 back and forth along the rails 6 and move the carriage longitudinally of the axis of a log on the rotating and supporting rollers 1.

The nozzle carriage 8 has a cylinder 14 rigidly carried thereby and extending perpendicularly to the carriage. A nozzle carrier 15 in the form of a hollow plunger is mounted in the cylinder 14 for reciprocatory movement therein.

The portion of the cylinder 14 below the packing 16, through which the plunger 15 extends, has an interior diameter greater than the exterior diameter of the nozzle carrier 15, as clearly shown in Figure 6 of the drawings; and this lower portion of the cylinder forms a manifold for high pressure water used for hydraulically removing bark from logs.

The high pressure water is delivered to the

manifold section 17 of the cylinder 14 from a suitable supply source (not shown) of high pressure water through an articulated conduit system 18.

The articulated conduit system 18 includes a conduit 19 which is pivotally supported by a suitable support 20. The conduit 19 is connected to the high pressure water supply source (not shown) through the conduit coupling 21, and it has its outlet end connected by a conduit coupling structure 22 to a pair of parallel conduits 23. The conduits 23 are connected by a conduit coupling 24 to the inlet pipe 25 which delivers the high pressure water into the manifold 17. The couplings 22 and 24 are constructed to provide universal couplings which will permit universal movement of the conduits 23 and 19 relative to the inlet pipe 25 and coupling 21 without disrupting the flow of the high pressure water to the manifold. These universal couplings are provided to permit movement of the nozzle structure during the debarking of a log without impedance to the flow of the high pressure water to the nozzle. The universal couplings may be of any approved form, but a particular construction of such coupling is shown in section in Figure 4 of the drawings.

The coupling 22 which is shown in section in Figure 4 of the drawings comprises a pair of cylinders 26 and 27 disposed at right angles to each other, which cylinders have heads 28 attached to their ends in fluid tight connection. The conduits are connected to the ends or heads 28 of the cylinders 26. Liners 29 are positioned in the cylinders 26 and are preferably threaded to the heads 28 so that the water flowing out of the conduits 19 will flow from both ends into the liner 29 and will flow out of this liner 29 through a plurality of transversely extending outlet openings 30 positioned intermediate the ends of the liner 29. The high pressure water flows from the openings 30 into a channel 31 formed in the wall of the cylinder and thence into a liner 32 in the cylinder 27. The liner 32 is identical in construction with the liner 29 and the water flowing from the channel 31 flows through the transverse openings in the liner 32 and out the ends of the liner into the conduits 23.

By provision of the coupling construction shown and just described the swivel joints of the pressure fluid delivering conduit structure will be hydraulically balanced, thus eliminating thrust on the swivel joints with the consequent wear of their parts. The pressure of the water flowing through the conduit system is quite high (approximately twelve hundred pounds per square inch) and consequently without the hydraulically balanced couplings relatively great wear on the parts of the swivel joints would insure.

The universal coupling 24 is of the same construction as the universal coupling 22, while the pivotal coupling 21 is of the same general construction, differing only in that it comprises but a single cylinder with a single liner therein. It is understood, of course, that the heads 28 of the various couplings are rotatable relative to the cylinders so as to permit universal movement of the various conduit sections.

The nozzle carrier 15 is hollow, as clearly shown at B in Figure 6 of the drawings, and it has a transversely extending wall 34 formed therein intermediate its ends to securely divide the lower section of the plunger-like carrier 15 from the upper section.

The wall of the carrier 15 directly below the

partition 34 is provided with a plurality of transversely extending openings 35 which establishes communication between the hollow interior of the lower portion of the nozzle carrier 15 with the manifold 17 so as to permit the high pressure water to flow from the manifold into the nozzle carrier and outwardly therefrom through the nozzle head 36 carried by the lower end of the nozzle carrier.

The nozzle carrier 15 is mounted for both reciprocatory and rotary movement in the cylinder 14 and it is packed at suitable desirable points indicated at 37 to prevent leakage of high pressure water past the carrier.

The upper portion of the nozzle carrier 15 is slightly larger than the lower portion and forms an annular shoulder or pressure differential area 38 against which the pressure of the water in the manifold 17 acts to force and hold nozzle 36 in its uppermost position as is shown in Figure 6 of the drawings.

The pressure of the pressure water in the manifold 17 is utilized for lowering and raising the nozzle 36, and the raising and lowering of the nozzle is controlled by a solenoid actuated valve structure 39.

When it is desired to lower the nozzle structure the solenoid actuated valve structure 39 is operated, through operation of a solenoid 40 (see Figures 4 and 8 of the drawings) to permit high pressure water to flow through a conduit 41 into a valve housing 42, past a valve 43, which is moved to its open position at such time and into and through a conduit 44 which delivers the high pressure water into an annular chamber 45 about the upper portion of the nozzle carrier 15. The high pressure water delivered into the chamber 45 passes through a plurality of passages 45' into a space 45a and against a head 46 carried by the upper end of the nozzle carrier 15. The head 46 has a greater area subjected to the pressure of the high pressure water than the area of the shoulder 38 so that the high pressure water acting upon the head 46 will overcome the pressure of the high pressure water acting on the shoulder 38 and will move the nozzle carrier 15 and nozzle 36 downwardly. By control of the valve 39 such movement may be arrested at any point within the range of movement of the nozzle carrier and nozzle. When it is desired to raise the nozzle the valve structure 39 is operated to seat the valve 43 and cut off the flow of high pressure water to the annular chamber 45, and a valve 47 is opened at the same time, by means of its solenoid 47' to allow pressure fluid from the chamber 45 to flow through a pipe 47a outwardly through an exhaust conduit 49, thus relieving the pressure against the head 46 and permitting the pressure of the high pressure fluid against the shoulder 38 to move the nozzle into its upward position. By control of the valve structures 39 and 47 the bleeding off of the pressure fluid from the chamber 45 may be controlled and when both valves 39 and 47 are closed the nozzle will be held in any adjusted position within its range of movement. Thus the nozzle 36 may be adjusted radially of the axis of a log carried by or mounted upon the supporting and rotating rollers 1 and the distance between the nozzle 36 and the log may be varied to suit particular conditions met with in debarking particular types of logs, as well as adjusted to regulate the distance from the log in accordance with the diameter of the log so as to be certain to obtain the desired erosive action of the

jet or jets of high pressure water projected from the nozzle 36 onto the log.

The resistance to barking or the removal of bark from logs varies with the type and age of the log or timber, thickness of the bark, season of the year when the log was cut, the time between cutting and removal of the bark and a number of other factors. The contributing factors effecting the hydraulic removal of the bark from the logs may vary with each log and, consequently, quick adjustment of the nozzle head for the required degree of debarking is desirable. To provide such quick adjustment of the nozzle head, means is provided in the present invention for rotating the nozzle head 36 and the nozzle carrier 15 relative to the cylinder 14 and, consequently, relative to the nozzle carriage 8, which rotary adjustment of the nozzle head cooperates with the adjustment provided by means of the pressure differential areas on the nozzle carrier as above described.

Various structures may be provided for rotating the nozzle head 36 without departing from the function of the present invention, and one structure for providing such rotation is illustrated in the drawings; but it is to be understood that the invention is not to be limited to the specific mechanism illustrated for rotating the nozzle, but only by the scope of the pendant claims.

In the form of nozzle rotating means shown in Figures 5 and 7 of the drawings, the head 46 of the nozzle carrier 15 has an opening or bore 50 extending longitudinally therethrough in which a flat key 51 is positioned. A rod 52 extends longitudinally through the opening 50 and downwardly into the upper hollow portion of the nozzle carrier 15 a distance corresponding to the length of movement of the nozzle carrier 15 relative to the cylinder 14. The rod 52 has a flat side 53 which engages against the key 51 so that when the rod 52 is rotated the nozzle carrier 15 will be correspondingly rotated.

The rod 52 passes outwardly through a head 54 of the cylinder 14, being packed by suitable packing wherever necessary to prevent leakage of high pressure water thereby. The protruding end of the rod 52 has a crank arm 55 connected thereto which is connected through a series of arms or levers 56 to a scotch yoke structure 57.

The scotch yoke structure 57 includes a block 58 to which the end lever of the linkage connection is pivoted. The block 58 slides transversely or laterally in a second block 59. The block 59 slides in a suitable guideway 60 in a direction transversely to the direction of movement of the block 58. The block 59 is connected by a piston rod 61 to a piston 62 which reciprocates in a cylinder 63.

The piston 62 is reciprocated in the cylinder 63 under action of the high pressure water and under control of a solenoid actuated valve 65, which may be of the same construction as the solenoid actuated valve 39 shown in detail in Figure 8 of the drawings.

A water supply conduit 66 is shown in Figure 4 of the drawings as connected to the inlet pipe 25, but it may be connected at any other suitable point in the supply line of high pressure water. The conduit 66 opens into the cylinder 63 on the side of the piston 62 to which the piston stem or rod 61 is connected, and when the valve 65 is operated to position to hold the nozzle 36 in such manner that the flat side of the jet of water issuing therefrom will be parallel to a vertical plane passing through the axis of a log

on the supporting rollers, the pressure fluid acting on the piston 62 will force it to its outward position in the cylinder 63. A supply line 61 for pressure water to the cylinder back or outwardly of the piston 62 is connected to the supply conduit 66 and passes through the valve structure 65, and a second communicating conduit 68 in the cylinder so that when the valve 65 is operated to rotate the nozzle 36 pressure water will be admitted into the cylinder 63 back of the piston 62. Due to the difference in the area of the ends of the piston acted upon by the high pressure water, caused by the piston rod 61, the piston 62 will then be forced inwardly against the pressure of the fluid in the inner end of the cylinder and operate the scotch yoke structure 57 for rotating the rod 52 and, consequently, rotating the nozzle carrier 15 and nozzle head 36. When a solenoid operated valve structure 65' is operated to open the conduit 68 in the outer end of the cylinder 63 to an exhaust line 69 the pressure in the cylinder 63 behind the piston 62 will be lower than the pressure inwardly of the piston 62 so that the piston will be forced outwardly to cause rotation of the rod 52, nozzle carrier 15 and nozzle head 36 in a reverse direction. When both valves 65 and 65' are closed the nozzle will be held locked in its adjusted position.

The nozzle head structure 36 is shown in detail in Figures 9 to 11 of the drawings and it comprises a body 70 which is attached in any suitable manner (not shown) to the lower end of the nozzle carrier 15. A nozzle attaching plate 71 is attached to the lower outer end of the body 70 in any suitable manner such as by bolts 72 and it carries a nozzle element 73. In Figures 9 to 11 of the drawings the nozzle element 73 is shown as an elongated plate having two outlet openings 74 therein separated by a suitable partition 75. These nozzle openings 74 are shaped so as to project a thin flat chisel-like stream of water against the surface of a log on the supporting and rotating rollers 1 so as to provide the maximum erosive action of the jets of high pressure water for removing the bark from the logs. The nozzle attaching plate 71 is provided with a suitable opening 76 of such size and shape as to prevent interference with the shape of the jets of water projected from the nozzle 73 and the housing 70 of the nozzle head is provided with a passage 77 so as to permit free, unimpeded flow of the water to the nozzle 73. The cross-section dimensions of the passages 77 gradually change between its inlet and outlet ends, the length increasing and the width decreasing at such rates, that the area in cross-section of passage 77 preferably decreases as the plane of cross-section approaches the outlet end. If it is so desired, the nozzle 73 may have a single opening therein or any desired number of openings, two openings 74 being shown as an example.

As will be noted from the drawings and the above description, the nozzle carrier 15 is rigidly carried by the nozzle carriage 8, and is perpendicular to the line of travel of the nozzle carriage 8 at all times, and the pressure water flows in a relatively long straight path from the entrance openings 35 of the nozzle carrier 15 to the nozzle 36. Thus, at all adjustments of the nozzle 36 and its carrier 15 relative to a log, there are no bends or tortuous ways in the flow path to set up eddies in the water, and to produce the undesirable results always occasioned by eddies in the flow of high pressure water.

As above stated, the resistance to barking or

removing the bark from logs varies due to a number of factors, and the contributing factors affecting the hydraulic removal of bark from logs may vary with each log, requiring quick adjustment of the nozzle head, and the above described structures which permit both rotary movement of the nozzle and movement of the nozzle in a plane substantially parallel to a plane passing through the axis of a log on the supporting and rotating rollers will permit of such quick adjustment and affords means for eliminating over-barking, undue splintering of the log, and the corresponding loss of wood.

Basically, the removal of bark from logs with the present hydraulic debarker is brought about by erosion through the effect of the impinging force or jet action of the water at high velocity applied on a confined area of the bark surface. The jet action may be taken generally to vary as the product of mass and velocity. These two components are also expressed by the gallons per minute flow of pressure water per unit width of barking kerf (representing mass) and the square root of the orifice pressure of the nozzle in pounds per square inch (representing velocity). Through the application of this basic principle an economical variation in the barking intensity is accomplished by varying the gallons per inch flow at constant pressure and constant gallons per minute supply of high pressure water. This is provided for by the rotation of the nozzle head which by angular positioning of the impinging jet varies the component mass or its equivalent gallons per inch of cutting kerf.

This is illustrated in Figures 12 and 13.

Figure 12 in the diagrammatic plan view thereof for rotative barking, that is wherein the log is rotated and the nozzle moved longitudinally along the log as in the present invention, and shows the inner section of the impinging jet and resultant cutting kerf on top of the log parallel with a plane passing through the longitudinal center of the log. The log is rotated by the rotating supporting rollers 1 and at the same time the jet of high pressure water is advanced longitudinally through the length of the log at a constant rate in increments of the dimension h per each revolution of the log. The jet of high pressure water may be rotated in either direction as indicated by the arrows and positioned at any angle g as at a , b , c , or f for varying the barking kerfs h . The length of the barking kerf h varies as the cosine of the angle g and determines the degree of barking or removal of the bark from the log. Complete removal of the bark from the log is accomplished in each complete stroke or movement of the jet throughout the length of the log.

Figure 13 shows the nozzle head for longitudinal barking of non-rotating logs, the nozzle head having been rotated 90° from its Figure 12 initial position or at right angles to a plane extending through the longitudinal center of the log in which it has minimum barking value, and is usable particularly on logs having tight bark difficult of removal. Variable intensity of the debarking jet is obtained in the same manner as disclosed and referred to in Figure 12 with the exception that the degree of bark removal increases as the nozzle moves towards a position where the flat side of the jet will be parallel to a plane extending through the longitudinal axis of the log.

The control of the jet just described precludes the necessity of applying other means such as

changing water pressure or gallons per minute of high pressure water supply to obtain corresponding results.

It will be understood that the invention is not to be limited to the specific construction or arrangement of parts shown, but that they may be widely modified within the invention defined by the claims.

What is claimed is:

1. In an apparatus for hydraulically debarking logs, a carriage for movement along a log to be debarked, a cylinder carried by said carriage, the lower portion of said cylinder forming a manifold for debarking pressure fluid, means for delivering fluid under pressure to said manifold, a hollow nozzle carrier mounted in said cylinder for longitudinal and rotary movement independently of the cylinder, a transverse partition in said nozzle carrier forming a lower pressure fluid passage and an upper space cut off from said fluid passage, means for rotating said nozzle carrier extending into said upper space, a nozzle carried by the lower end of the nozzle carrier, said nozzle carrier having openings therein near said partition to admit pressure fluid from said manifold into said fluid passage, a nozzle carried by the lower end of said nozzle carrier and means for moving said nozzle carrier longitudinally and rotatably independently of said manifold.

2. An apparatus for hydraulically debarking logs as claimed in claim 1 wherein said means for rotating said nozzle carrier consists of a rod having a flat thereon, a head on the upper end of said nozzle carrier having an opening therein provided with a flat for engagement with the flat of said rod, said rod slideable in said opening, and means for rotating said rod to rotate the nozzle carrier.

3. An apparatus for hydraulically debarking logs as claimed in claim 1 wherein said means for rotating said nozzle carrier consists of a rod having a flat thereon, a head on the upper end of said nozzle carrier having an opening therein provided with a flat for engagement with the flat of said rod, said rod slideable in said opening, pressure fluid actuated means for rotating said rod, conduits connecting said pressure fluid actuated means to said pressure fluid delivery means, and a valve for controlling delivery of pressure fluid to said pressure fluid actuated means.

4. An apparatus for hydraulically debarking logs as claimed in claim 1 wherein said nozzle is constructed to project a relatively thin flat chisel-like stream of fluid against a log to be debarked, said nozzle rigidly carried by said nozzle carrier to project the pressure fluid stream substantially axially of the carrier at all times, whereby movement of the carrier will vary the debarking intensity of a jet of fluid projected by the nozzle.

5. In an apparatus for hydraulically debarking logs, a carriage for movement along a log to be debarked, a cylinder carried by said carriage, the lower portion of said cylinder forming a manifold for debarking pressure fluid, means for delivering fluid under pressure to said manifold, a hollow nozzle carrier mounted in said cylinder for longitudinal and rotary movement independently of the cylinder, a nozzle carried by the lower end of said nozzle carrier, said nozzle carrier having openings therein to permit pressure fluid to enter the nozzle carrier from said manifold, means for rotating said

nozzle, means for moving said nozzle carrier longitudinally independently of the manifold, said nozzle being constructed to project a relatively thin flat chisel-like stream of fluid against a log to be debarked, said nozzle rigidly carried by said nozzle carrier to project the pressure fluid stream substantially axially of the carrier at all times whereby movement of the carrier will vary the debarking intensity of a jet of debarking fluid projected by the nozzle.

6. In an apparatus for hydraulically debarking logs, a carriage for movement along a log to be debarked, a cylinder carried by said carriage, the lower portion of said cylinder forming a manifold for debarking pressure fluid, means for delivering fluid under pressure to said manifold, a hollow nozzle carrier mounted in said cylinder for longitudinal and rotary movement independently of the cylinder, a nozzle carried by the lower end of said nozzle carrier, said nozzle carrier having openings therein to permit pressure fluid to enter the nozzle carrier from said manifold, means for rotating said nozzle, means for moving said nozzle carrier longitudinally independently of the manifold, said nozzle being constructed to project a relatively thin flat chisel-like stream of fluid against a log to be debarked, said nozzle rigidly carried by said nozzle carrier to project the pressure fluid stream substantially axially of the carrier at all times whereby said means for rotating the nozzle together with said means for moving the nozzle carrier longitudinally will vary the position of the nozzle relative to a log to be debarked to vary the mass and velocity of a jet of water projected by the nozzle against a predetermined area of surface of a log for varying the erosive action of a pressure fluid jet on a log.

7. In an apparatus for hydraulically debarking logs, a carriage for movement along a log to be debarked, a cylinder carried by said carriage, the lower portion of said cylinder forming a manifold for debarking pressure fluid, means for delivering fluid under pressure to said manifold, a hollow nozzle carrier mounted in said cylinder for longitudinal and rotary movement independently of the cylinder, an annular shoulder formed on said nozzle carrier intermediate its ends and exposed to pressure of fluid in said manifold for urging said nozzle carrier upwardly relative to the manifold, a head formed upon the upper end of said nozzle carrier and having greater cross sectional area than said shoulder, means for delivering pressure fluid from said pressure fluid delivery means against said head to move said nozzle carrier downwardly against the pressure exerted against said shoulder, and a valve for controlling delivery of pressure fluid against said head.

8. An apparatus for hydraulically debarking logs as claimed in claim 7 including hydraulically operated means for rotating said nozzle carrier, means for delivering pressure fluid from said pressure fluid delivery means to said hydraulic means and a valve for controlling delivery of pressure fluid to said hydraulic means.

9. Apparatus for hydraulically debarking logs as claimed in claim 7 including a nozzle rigidly carried by the lower end of said nozzle carrier, said nozzle constructed to project a relatively thin flat chisel-like stream of fluid against a log to be debarked whereby movement of the carrier would vary the debarking intensity of a jet of debarking fluid projected by the nozzle.

11

10. An apparatus for hydraulically debarking logs as claimed in claim 7 including hydraulically operated means for rotating said nozzle carrier, means for delivering pressure fluid from said pressure fluid delivery means to said hydraulic means and a valve for controlling delivery of pressure fluid to said hydraulic means, said nozzle constructed to project a relatively thin flat chisel-like stream of fluid against a log to be debarked whereby said means for rotating the nozzle together with the means for moving the nozzle carrier longitudinally will vary the position of the nozzle relative to a log to be debarked to vary the mass and velocity of a jet of water projected by the nozzle against a predetermined area of surface of a log for varying the corrosive action of the jet on a log.

11. Apparatus for hydraulically debarking logs as claimed in claim 7 including a nozzle rigidly carried by the lower end of said nozzle carrier and having an elongated relatively narrow outlet opening therein arranged so that water projected from the nozzle will always be projected parallel to the longitudinal axis of the nozzle carrier, means for rotating said nozzle carrier to vary the angle at which the thin chisel-like stream of water projected from said nozzle will strike a log to be debarked at different angles relative to the longitudinal axis of the log.

12. Apparatus for hydraulically debarking logs as claimed in claim 7 including a nozzle rigidly carried by the lower end of said nozzle carrier and having an elongated relatively narrow outlet opening therein arranged so that water projected

12

from the nozzle will always be projected parallel to the longitudinal axis of the nozzle carrier, means for rotating said nozzle carrier to vary the angle at which the thin chisel-like stream of water projected from said nozzle will strike a log to be debarked at different angles relative to the longitudinal axis of the log, said rotating means comprising hydraulically operated means connected to the nozzle carrier, means for delivering pressure fluid to said hydraulic means and a valve for controlling delivery of pressure fluid to said hydraulic means.

JOSEPH E. HOLVECK.
